US0D1098030S

(12) **United States Design Patent** (10) Patent No.: **US D1,098,030 S**
(45) Date of Patent: ** Oct. 14, 2025

(54) **ELECTRICAL CONNECTOR**

(71) Applicant: **KYOCERA Corporation**, Kyoto (JP)

(72) Inventor: **Hiroaki Watanabe**, Yokohama (JP)

(73) Assignee: **KYOCERA CORPORATION**, Kyoto (JP)

(**) Term: **15 Years**

(21) Appl. No.: **29/944,834**

(22) Filed: **May 30, 2024**

(30) **Foreign Application Priority Data**

May 22, 2024 (JP) ..... 2024-010282 D

(51) **LOC (15) Cl.** **13-03**

(52) **U.S. Cl.**

USPC **D13/133**

(58) **Field of Classification Search**

(57) **CLAIM**

The ornamental design for a electrical connector as shown and described.

DESCRIPTION

FIG. 1 is a front perspective view of an electrical connector showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.
